UNITED STATES PATENT OFFICE.

WILLIAM C. TINGLE, OF WASHINGTON, MISSOURI.

MOISTENING-MACHINE.

1,154,552.

Specification of Letters Patent. Patented Sept. 21, 1915.

Application filed April 15, 1914. Serial No. 832,119.

To all whom it may concern:

Be it known that I, WILLIAM C. TINGLE, citizen of the United States, residing at Washington, in the county of Franklin and 5 State of Missouri, have invented certain new and useful Improvements in Moistening-Machines, of which the following is a specification.

My invention relates to machines for wetting materials, especially such as are of a fibrous nature, for example, leather, to soften the same and render it pliable and easy to work.

It is a well known fact that the fibers 15 of a leather inner sole have to be moistened before the machine commonly known as the "welter" can sew the welt, upper and inner sole together. Heretofore it has been the custom to apply water to the outside of the 20 inner sole, either with a can, similar to an oil can, or by dipping the sole in water or other suitable liquid. In reality, the only 25 part of an inner sole that needs moistening is the "between substance" or, in other words, that part of the inner sole directly 30 between the bottom of the two knife cuts, which form the outside and inside channels.

Such being the case, the object of the invention is to apply the water or other 35 moistening fluid directly to the "between substance" at the bottom of the inside channel of the inner sole and not necessarily to other parts as heretofore.

The above and additional objects are accomplished by such means as are illustrated 40 in their preferred embodiment in the accompanying drawings, described in the following specification and then more particularly pointed out in the claims which are appended hereto and form a part of this application.

In describing my invention in detail reference will be had to the accompanying drawings wherein like characters denote like or 45 corresponding parts throughout the several views, and in which:

Figure 1 is an end view of a wetting machine constructed in accordance with the present invention; Fig. 2 is a side elevation 50 of the machine; Fig. 3 is a rear end view; Fig. 4 is a detail elevation, partly in section, of the nozzle; Fig. 5 is an enlarged section on the line 5—5 of Fig. 4; Fig. 6 is an 55 enlarged elevation, partly broken away, of the operating shaft and feed wheel mounted thereupon; and Fig. 7 is an enlarged longi-

tudinal sectional view of the head portion of the machine.

Referring now to the drawings by numerals, 1 designates a table, stand or other suitable support upon which the machine comprising the present invention is mounted. The machine in its preferred embodiment includes an upright frame portion 2 having a lateral angularly disposed extension 3 integral therewith, said extension terminating in an enlargement or head portion 4 provided with a longitudinal bore or opening 5. Within said bore or opening 5 a suitable sleeve 6 is arranged, said sleeve having 70 formed upon one of its ends, an annular flange 7 so positioned relatively to the head portion 4 of the frame as to rest thereupon in a manner apparent upon reference to Fig. 7 of the drawings. Said flange 7 with a 75 collar 8 mounted upon the said sleeve 6, provides a means whereby longitudinal movement of the sleeve within the bore 5 is prevented. An operating shaft 8' adjustable longitudinally with respect to the sleeve 6 80 but rotatable therewith is arranged to pass through the bore of the said sleeve, said shaft having mounted upon its lower end a feed or operating wheel 9, the lateral faces of which are beveled oppositely, one of the 85 said lateral faces being corrugated as indicated at 10 for a purpose to be hereinafter fully described. Upon the opposite or upper end of the said shaft 8' a pulley wheel 10' is mounted, said pulley wheel being 90 keyed or otherwise fixedly secured to the said shaft and provided with a peripheral groove for the reception of a strap 11. A suitable bracket 12 is fixedly secured to the upright portion of the machine frame 2, the 95 said bracket supporting a pair of spaced apart pulley wheels 13 also peripherally grooved for the reception of the said strap 11, the strap being arranged over the pulleys 10' and 13 in a manner illustrated to 100 advantage in Fig. 3 of the drawings. By this arrangement, it is apparent that the shaft 8' may be driven or rotated at a rate of speed suitable to the proper operation of the device.

A foot or nozzle 14 is attached to the head 105 4 of the frame, said nozzle being extended at an angle as indicated at 15 to terminate at a point adjacent the corrugated face of the feed wheel 9. Within the extended portion 110 15 of the nozzle, a comparatively small pipe section 16 is fitted, said pipe section having

attached thereto in any suitable manner a supply pipe 17 through which water or other suitable liquid under pressure is forced.

Operation of the machine is as follows: 5 The shoe sole acted upon should be so arranged, inner sole uppermost, relatively to the extended portion of the nozzle 14 as to cause the said extension to fit the inside channel of the inner sole, the corrugated 10 face 10 of the wheel 9 being thus directly engageable with the said sole. A rotation of the wheel at a proper speed will feed the sole if properly held. Water or other moistening fluid being forced through the pipe section 16, it is apparent that the said fluid is finally discharged into the inside channel 15 of the sole and directly to the "between substance" whereby a moistening of the between substance only is effected.

20 From the foregoing, taken in connection with the accompanying drawings it is apparent that the operation of the device is simple in the extreme; that the shoe soles may be conditioned properly prior to action 25 thereupon by the "welter"; and that various objectionable features heretofore existing where the whole sole was moistened are eliminated.

In reduction to practice, I have found that 30 the form of my invention, illustrated in the drawings and referred to in the above description, as the preferred embodiment, is the most efficient and practical; yet realizing that the conditions concurrent with the 35 adoption of my device will necessarily vary, I desire to emphasize the fact that various minor changes in details of construction, proportion and arrangement of parts may be resorted to, when required, without sacrificing any of the advantages of my invention, 40 as defined in the appended claims.

Having thus fully described my invention, what I claim as new and desire to secure by Letters Patent, is:—

45 1. A machine for wetting only a limited portion of a shoe sole consisting in means directly engaging with the sole acted on for advancing it during a wetting operation, and means discharging adjacent the 50 point of engagement of the advancing means

with the sole for wetting the sole during its advancement.

2. A wetting machine for treating leather and like materials including a suitable support, a shaft, means on the shaft and directly engaging with the material acted on to advance it during a wetting operation, means discharging adjacent the point of engagement of the advancing means with the sole for wetting the material in a defined path, and means to drive the shaft.

3. In a machine for treating leather and the like materials, a body portion, an arm extending at an angle to said body, a shaft mounted for rotation at the free end of said arm, means operating to rotate said shaft, a corrugated wheel rotatable with said shaft and engageable with the material acted upon, the rotation of said wheel when in engagement with said material being adapted to advance the latter, a nozzle engageable with the material acted upon adjacent the said wheel, and means for supplying moisture to the material through said nozzle, during its advancement, as and for the purpose set forth.

4. A wetting machine for treating leather and the like materials including a body portion, an arm extending at an angle to said body portion, a hollow head at the free end 20 of said arm, a sleeve rotatable within said head, a shaft carried by said sleeve and adjustable relatively to the said head, means actuatable to rotate said shaft, a corrugated wheel rotatable with said shaft and engageable with the material acted upon to advance the same during a wetting operation, a nozzle carried by said head and disposed adjacent said wheel, said nozzle being engageable with the said material, and means for 25 supplying liquid to said nozzle to wet the material during its advancement, as and for the purpose set forth.

In testimony whereof I affix my signature in presence of two witnesses.

WILLIAM C. TINGLE.
